FURNACE

Raymond R. Dupler, deceased, late of Toledo, Ohio, by Anna Gertrude C. Dupler, executrix, 744 Euclid Ave.,
Toledo, Ohio 43605

Filed June 5, 1972, Ser. No. 260,045

Term of patent 14 years

Int. Cl. D23—03

U.S. Cl. D23—72

FIG. 1

FIG. 1 is a front perspective view of the furnace showing the new design; and

FIG. 2 is a rear perspective view of the furnace shown in FIG. 1.

The opposite side of the furnace which does not appear on the drawings is identical in appearance to the side which is illustrated.

I claim:

The ornamental design for a furnace, as shown and described.
